(57) **CLAIM**

The ornamental design for an angled hinge hanger with an elongated vertical tube, as shown and described.

DESCRIPTION

FIG. 1 is an isometric top view of an angled hinge hanger with an elongated vertical tube, showing my new design;
FIG. 2 is an isometric bottom view thereof;
FIG. 3 is a front elevation view thereof;
FIG. 4 is a left elevation view (at 90° from the front view)
thereof;
FIG. 5 is a back elevation view thereof;
FIG. 6 is a bottom view thereof; and,
FIG. 7 is a top view thereof.
